UNITED STATES PATENT OFFICE.

AQUILA B. MARSHALL, OF NEW YORK, N. Y., ASSIGNOR OF TWO-THIRDS
TO EDWIN E. DICKINSON, OF SAME PLACE, AND CHARLES B. BOYNTON,
OF NEWARK, NEW JERSEY.

DESIGN FOR A PUMP-CASING.

SPECIFICATION forming part of Design No. 24,932, dated November 26, 1895.

Application filed October 23, 1895. Serial No. 566,658. Term of patent 7 years.

To all whom it may concern:

Be it known that I, AQUILA B. MARSHALL,
of New York city, in the county and State of
New York, have invented and produced a new
5 and original Design for a Pump-Casing, of
which the following is a full, clear, and exact
description.

Reference is to be had to the accompanying
drawings, forming a part of this specification,
10 in which—

Figure 1 is a perspective view of a pump-
casing embodying my new design, and Fig. 2
is an edge view thereof.

The leading feature of my design resides in

a pump-casing having a cylindrical portion 15
and a broadened end. Minor features reside
in the annular head at the junction of the cy-
lindrical portion and the flat end, the round
stud-like formations on opposite sides of the
flat portion, and a similar formation on the 20
end of the cylindrical portion.

I claim—

The design for a pump casing herein shown
and described.

AQUILA B. MARSHALL.
